UNITED STATES PATENT OFFICE

FRANK J. QUIGAN, OF JACKSON HEIGHTS, NEW YORK

DESIGN FOR A HAND BAG

Application filed October 23, 1929. Serial No. 33,146. Term of patent 14 years.

To all whom it may concern:

Be it known that I, FRANK J. QUIGAN, a citizen of the United States, residing at Jackson Heights, Long Island, in the county of Queens and State of New York, have invented a new, original, and ornamental Design for Handbags, of which the following is a specification, reference being had to the accompanying drawing, forming part thereof.

Fig. 2 is a top plan view;

Fig. 3 is a fragmentary elevation of the hand bag showing the opposite side of the frame clasp from that seen in Fig. 1, and

Fig. 4 is a similar fragmentary end elevation.

I claim:

The ornamental design for a handbag, as shown.

FRANK J. QUIGAN.
